UNITED STATES PATENT OFFICE

1,947,099

LIQUID GAS VAPORIZER

Maurice E. Painter, Dayton, Ohio

Application July 6, 1931. Serial No. 548,847

2 Claims. (Cl. 257—248)

This invention relates to improvements in method of and apparatus for reconverting liquefied hydrocarbon gases, and has for its primary object the method of reconverting hydrocarbon gases, which have been reduced to a liquid, to their gaseous state.

A further object is to construct an apparatus by means of which liquefied hydrocarbon gases are readily reconverted to gaseous state.

10 A further object is to construct an apparatus for reconverting liquefied hydrocarbon gases in which the pressure at which the liquid gas is introduced and at which the reconverted gas is withdrawn can be accurately controlled.

15 A further object is to construct an apparatus for reconverting liquefied hydrocarbon gases which has a large exposed surface area whereby the accumulation of frost thereon, due to temperature reduction during the reconverting process, is practically eliminated. Consequently, the apparatus can be used continuously over long periods of time, and the use of artificial heat to assist such reconversion is unnecessary except in cases where the temperature around the reconverting unit is below that required for gasification.

In the drawing:—

Fig. 1 is a side elevation of my device attached to a drum with parts broken away and in section.

30 Fig. 2 is a fragmental view with parts in section of the upper end of the spray pipe.

Fig. 3 is a similar view of the lower end of the spray pipe.

35 Fig. 4 is a plan view of one of the deflectors made use of.

In carrying out my invention, 5 represents a drum in which the liquefied gas is stored. 6 is a valve secured to the upper end of the drum for the release of the contents. The valve 6 is provided with a pipe 7 which extends into the drum 5 and terminates near the bottom of the drum. The valve 6 is provided with the usual valve stem 8 for the attachment of a wrench for opening and closing the valve. A conduit 9 is attached to the valve by means of a shackle 10. The opposite end of the conduit 9 is attached to a pressure regulating valve 11. This valve is secured to a boss 12 which is formed integral with the top 13.

40 The boss 12 is provided with a port 14 in which is screw threaded a sleeve 15. The sleeve is provided at its upper end with a slot 16 to receive a screw driver blade so that the same can be inserted and removed from the boss 12. The port

14 is preferably formed concentric with the hollow member 17.

Secured at one end in the sleeve 15 is a spray pipe 18. This spray pipe extends downwardly into the hollow member 17 and has its lower end closed with a plug 19. The spray pipe is provided with a plurality of longitudinally spaced openings 20. These openings may be diametrically opposite each other or may be arranged in any other suitable manner.

Surrounding the spray pipe 18 are deflectors 21. These deflectors are preferably located just below the openings 20 and are inclined upward slightly so as to deflect the spray and break it up into a mist. The deflectors 21 are preferably secured to the spray pipe 18 by slipping them on the pipe and then bending them with a pair of pliers, the bending being illustrated in Fig. 3. This causes the deflectors to tightly grip the pipe 18.

A bottom 22 closes the bottom end of the hollow member 17. This bottom 22 is provided with a passageway 23 which communicates with the interior of a hollow member 24 also carried by the bottom 22. The top 13 closes the upper end of the hollow member 24 and is provided with a boss 25 through which a port 26 is formed. The boss 25 carries a pressure regulating valve 27 to which is attached a pipe 28, this pipe leading to either the heating or lighting device where the reconverted gas is to be used.

Among the gases which may be reconverted by my method and apparatus are a mixture of propane and butane, the mixture being preferably thirty per cent (30%) of propane and seventy per cent (70%) of butane. These two gases are obtained in liquefied form at oil wells or refineries, and, upon being mixed and brought into contact with the atmosphere or a surface having a temperature as low as 40° F., gasify. The mixture of gases is placed in the drum 5 under a pressure of from seventy to one hundred pounds, and, after the conduit 9 has been connected to the pressure regulating valve, the valve 6 is opened and the pressure regulating valve 11 regulated so that the liquefied gases will enter the spray pipe 18 at a pressure of about four pounds. As soon as the valve 6 is opened the pressure in the drum is lowered and a portion of the liquefied gases in the drum commences to turn to its gaseous state, and in so doing exerts pressure on the liquid and forces the liquid in the drum upwardly through the pipe 7, conduit 9, through the valve 11, and into the spray pipe 18.

The liquid issues from the openings 20 in the form of a fine spray which, upon striking the 110

upturned portions of the deflectors 21, is converted into a mist, and this mist coming in contact with the surface of the hollow member 17 exchanges heat therewith and is reconverted into a gas suitable for lighting and heating purposes.

The gas passes from the hollow member 17 through the passage 23 and into the hollow member 24, from which it passes through the port 26, pressure regulating valve 27 where it is reduced to a relatively low pressure of only a few ounces, into the pipe 28, and then either to the heating or lighting unit.

My purpose of mounting the spray pipe 18 in a sleeve which is readily removable from the port 14 is that in the event large quantities of gas are desired this spray pipe may be removed and replaced by another spray pipe having more openings therein and also more deflectors. The deflectors are of such diameter that they will pass readily through the port 14 so that the change of spray pipes can be made by simply removing the pressure regulating valve 11. It is understood, of course, that the hollow members 17 and 24, which constitute the expander, are secured to the top 13 and bottom 22 in such a manner that leakage of gas will not occur. This may be done either by welding, soldering, or other well known methods.

While I have mentioned propane and butane specifically as the gases to be reconverted from a liquid to a gaseous state, I do not desire to limit myself thereto as there are other gases which can be reconverted from a liquid to a gaseous state in the same manner.

I may also increase the surface area of the hollow members 17 and 24 by corrugating the same and in this way increase the heat exchanging capacity of the expander without materially in-

creasing the size of the expander. This form of construction is desirable where large quantities of gas are required, or where sudden increased demands for gas are made.

What I claim and desire to secure by Letters Patent is:

1. An apparatus for converting liquefied hydrocarbon gases comprising a pair of hollow members, a base for said members, a passageway formed in said base and communicating at its ends with the interior of said hollow members, a top for said hollow members, an inlet port formed in said top and communicating with the interior of one of said members, a spray pipe removably carried by said top, said spray pipe being in communication with said inlet port, an outlet port formed in said top and communicating with the interior of the remaining hollow member, and pressure regulating means carried by said top for regulating the pressure of liquid entering into and gases passing from said hollow members.

2. An apparatus for converting liquefied hydrocarbon gases comprising a pair of hollow members, means for closing opposite ends of the members and for spacing said members to expose their circumferential area to atmospheric temperatures comprising a base having a passageway for providing communication between said members and a top having an inlet port in communication with one member and an outlet port communicating with the other member, a spray pipe mounted in the inlet port and extended into the respective hollow member, and pressure regulating means for regulating the pressure of liquid entering the inlet port and the pressure of gas passing from the outlet port.
